UNITED STATES PATENT OFFICE.

GEORGE B. SNOW, OF LONG BEACH, CALIFORNIA, ASSIGNOR TO THE SNOW DENTAL COMPANY, OF BUFFALO, NEW YORK, A CORPORATION OF NEW YORK.

TRIAL-PLATE CLAMP.

1,119,051.

Specification of Letters Patent.

Patented Dec. 1, 1914.

Application filed April 13, 1914. Serial No. 831,532.

To all whom it may concern:

Be it known that I, GEORGE B. SNOW, of the city of Long Beach, in the county of Los Angeles and State of California, have 5 invented certain new and useful Improvements in Trial-Plate Clamps, of which the following is a specification.

This invention relates to a device used by dentists in the course of the construction 10 of full upper and lower dentures, for holding and retaining the trial plates in their relative positions to each other; the same being determined by trial and adjustment of the plates in the mouth of the patient, 15 and fixing the said trial plates in their relative positions when transferring them from the mouth to the articulator.

The object of the invention is the production 20 of a device by which the trial plates will be more securely held in their proper relation to each other, and which can be more easily handled and applied than are those in common use.

In the accompanying drawing, Figure 1 25 shows the upper and lower trial plates and their respective plaster casts, with one of my clamps applied to retain the trial plates in their correct relative positions; the long axis of the clamp being disposed vertically. 30 Fig. 2 is a similar illustration of the trial plates, plaster casts and clamp, but in this instance, the clamp is applied with its long axis disposed horizontally. Fig. 3 is a lateral view of my clamp. Fig. 4 is an end 35 view of the same.

One clamp is applied to each side of the trial plates, in the region occupied by the bicuspid teeth, as shown in Figs. 1 and 2.

The trial plates are composed of two 40 parts; a thin plate, which covers that portion of the roof of the mouth and gums which is to be hereafter covered by the dentures, and a thick portion or rib, which represents the teeth which are to be mounted 45 upon the plate.

In the drawings, in which similar numerals denote similar parts in the different figures, 1 denotes the upper plaster cast, 2 the upper trial plate, 3 the rib, or part corresponding to the alveolar border on the same, 4 the rib of the lower trial plate 5, and 6 the lower plaster model. The clamp 7 is intended to be punched from sheet

metal with its prongs 8 radiating diagonally from its body; so that when bent at 55 right angles thereto, their flat surfaces will be disposed diagonally to the long and short axes of the body of the clamp, as shown. After the trial plates have been fitted to the mouth, and their alveolar ridges 2-3 60 trimmed so that they come into close contact, and their labial and buccal surfaces trimmed to form a continuous surface which gives the correct expression to the lips and cheeks, they are clamped together 65 by forcing the prongs 8 of the clamp 7 into the ribs 2 and 3, as shown in Figs. 1 and 2. If the ribs are of considerable thickness, the clamp 7 may be attached thereto with its long axis vertical, as shown in Fig. 1. If 70 the ribs are thinner, the clamp is attached with its long axis horizontal, in order to avoid wounding the gum of the patient, as shown in Fig. 2.

In order that the clamp may be conveniently handled, I show a flange or projection 75 9, forced up from the body of the clamp 7 by means of a half punch. By means of this flange, the clamp 7 may be picked up and carried to place by using the 80 ordinary dentist's foil tweezers. These will hold the clamp securely if they are applied to the flat surfaces of the flange 9, and will carry the clamp to the trial plates as shown in Fig. 1, with its long axis vertical. But 85 it is necessary that the tweezers should be applied in a line with the lips of the patient, or the occlusal surfaces of the trial plate, and if it is desired to apply the clamp 7 with its long axis horizontal, as shown in 90 Fig. 2, the hold of the tweezers upon the edges of the flange 9 would be insecure. I therefore show a perforation 10 in the flange 9, into which a slim tapered instrument 11 can be forced, and will hold the 95 clamp so that it can be conveniently applied as shown in Fig. 2. And if, as is sometimes the case, it is desired to heat the clamp 7, before its insertion into the ribs 2-3 of the trial plates, the flange 9 affords 100 a means of carrying it into the flame of a lamp for that purpose.

Having thus described my invention, I claim as new and patentable,

1. A trial plate clamp having four prongs 105 and a body with long and short axes; the

said prongs having their flat sides disposed diagonally to the said axes; substantially as described.

2. A trial plate clamp formed from sheet metal, having a flange or handle turned upward from its body; substantially as described.

3. A trial plate clamp formed from sheet

metal, having a flange or handle turned upward from its body, with a perforation in therein; as and for the purposes set forth.

GEORGE B. SNOW.
